MARIUS GUYOT, OF CLEVELAND, OHIO, ASSIGNOR TO ALUMINUM COMPANY OF AMERICA, OF PITTSBURGH, PENNSYLVANIA, A CORPORATION OF PENNSYLVANIA

AUTOMATIC CORE CHILLING DEVICE

Application filed October 22, 1930. Serial No. 490,382.

My invention relates broadly to a device for chilling metal, and more particularly to a method and apparatus for automatically chilling permanent mold cores and the like to a predetermined degree.

In permanent mold or chill casting the metallic structure produced in the cast article is dependent to a substantial degree upon the rapidity with which the molten metal is chilled from the freezing or solidification point and, therefore, upon the initial temperature of the mold and core parts when the molten metal is poured. It is customary, in operating a mold of this type, to assemble 10 the core parts within the mold, lock the mold halves together, and pour the metal. As soon as the metal has set, which may be readily and accurately determined by the operator through observation of the condition of the 15 gate, the mold halves are loosened and the core members removed. Since the molten metal is normally maintained at a constant temperature during a series of casting operations, the core members are heated to substantially the same temperature during each 20 operation. It has heretofore been customary for the operator to dip the heated core members into a pot of cooling water after each casting operation to restore them to the desired 25 initial temperature for another operation. The operator holds the cores in the water until, in his judgment, the temperature has been reduced to the desired initial temperature for the next casting operation. It is 30 found that considerable skill is required on the part of the operator to maintain even an approximate uniformity of initial core temperature during a series of operations.

Accordingly, the principal object of my 35 invention is to eliminate the personal equation in the chilling or cooling of the core members during a series of casting operations, and to maintain a substantially constant initial core temperature.

Another object of the invention is to pro-

vide an improved method and apparatus for automatically cooling a heated article a predetermined amount.

Other objects and advantages relating to details of construction and operation will appear hereinafter.

In the accompanying drawings, which illustrate a preferred embodiment of my invention:

Fig. 1 is a sectional view of a chilling apparatus, showing a core member in position before immersion into the cooling medium. This section is taken on a plane through the line 1-1 of Fig. 3.

Fig. 2 is a sectional view taken on a plane 60 through the line 2-2 of Fig. 1.

Fig. 3 is a plan view of the apparatus.

Fig. 4 is a sectional view taken on a plane 65 through the line 4-4 of Fig. 3, showing the means for supporting a side core member.

Referring to the drawings, the apparatus includes a pot or the like 5 designed to contain a cooling fluid, such as water. Posts 6 and 7 are secured to the pot 5 on opposite sides thereof and extend above the pot to support a U-shaped yoke 8. Preferably the yoke 8 is provided with lateral arms 9 apertured to receive and slide upon the supporting posts 6 and 7, and provided with set screws 10 to secure the yoke in any desired position of 70 vertical adjustment.

In the embodiment shown, the bottom of the pot 5 is formed with a boss 11 having opposed tapered bores 12 and 13 separated by an annular shoulder 14. A discharge pipe 15 80 is secured in the bore 13 and may, if desired, constitute a support for the apparatus. An axially aligned pipe 16 is secured in the bore 12 with its lower end engaging the shoulder 14. The pipe 16 extends upwardly within 85 the pot 5 and is formed at its upper end with an outwardly turned annular flange 17.

A plate 18 integral with the side wall of the pot 5 extends upwardly and outwardly therefrom to form a supporting rack for core 90

members. As shown, the plate 18 terminates in a supporting edge 20 designed to receive an outwardly turned flange 21 of a core member 22 to suspend the same in the pot. A water inlet conduit 23 extends into the pot and preferably terminates adjacent the bottom thereof. In normal operation a continuous flow of water enters the pot through the conduit 23.

10 Slidably mounted on the pipe 16 is a sleeve 24, counter bored from its upper end to form a shoulder 25 which normally abuts against the flange 17. The sleeve 24 has a plurality of circumferentially aligned openings 26 disposed adjacent the upper end 27 thereof. The end 27 is threaded to receive a plug 28 having a plurality of vents or apertures 29 therethrough. Disposed between the plug 28 and the flange 17 is a helical spring 30 which is normally effective to hold the shoulder 25 in contact with the flange 17. A sleeve 31 fits over the sleeve 24 and has a plurality of apertures 32 which co-operate with the openings 26 to regulate the rate of flow of fluid from the interior of the pot into the pipe 16. A set screw 33 is arranged to secure the sleeve 28 in any desired adjusted position relative to the sleeve 24.

30 In the operation of the device water or other cooling fluid at a substantially constant temperature enters the pot through the conduit 23, passes through the registering openings 32 and 26 into the pipe 16, and is discharged through the pipe 15. The water level in the pot is therefore determined by the vertical position of the openings 26 and 32, as shown at A in Fig. 4. After a casting has been poured, the operator removes the core sections from the mold. In the usual type of permanent mold for casting pistons and the like, for use with which the illustrated embodiment of the core chilling apparatus is particularly adapted, the core consists of a comparatively large central section, illustrated generally at 34 in Fig. 1, having a supporting flange 35 and a pair of smaller side sections 22 recessed to form bosses on the interior of the casting. The central section 34 is placed on the plug 28, the upper portion thereof being guided and supported by the U-shaped yoke 8. The side sections are then suspended from the supporting edge 20 of the plate 18. The weight of the central section 34 overcomes the force of the spring 30, causing the sleeve 24 to slide downwardly over the pipe 16. The supporting flange 35 of the core section 34 engages the yoke 8, and limits the downward movement of the sleeve 24, the height of the yoke being adjusted along the rods 6 and 7 to produce the most desirable results.

Upon the initial downward movement of the sleeve 24 the end of the core section 34 is immersed in the water in the pot and chilled. Since the registering openings 26

and 32 are submerged by the movement of the sleeve 24, the water in the pot drains through these openings until the liquid level is again stabilized below the upper end 27 of the sleeve 24, at which time the core section 34 is no longer in contact with the water. The size of the openings and the rate at which the water flows therethrough is adjusted by circumferential movement of the sleeve 31 until the operation reduces the temperature of the heated core to the desired initial temperature for another casting operation.

The side core sections 22 are similarly chilled, since the ends thereof dip into the water at the higher water level and are out of contact with the water at the lower level.

After the core members have been chilled, they are removed from the apparatus and again assembled in the mold. When the center core section is lifted, the spring 30 restores the sleeve 24 to its uppermost position and the continuous inflow of water through the conduit 23 again raises the water level to its initial position.

It will be seen that the height of the yoke, the rate of inflow of the water, and the size of the discharge openings may be readily adjusted to chill the core sections a desired amount, and that the selected initial temperature is thereafter automatically maintained.

Although the foregoing description is necessarily of a detailed character in order that my invention may be fully disclosed, it is to be understood that the invention is not limited to the embodiment illustrated, but is susceptible of modification and re-arrangement of parts. For example, the apparatus may be readily designed to receive the various core sections of any type of mold. In its broader aspects, my invention may also be utilized for other purposes than chilling cores, being operable to chill or quench any heated article a desired pre-determined amount.

I claim:

1. Apparatus for chilling cores comprising a receptacle adapted to contain a cooling liquid, means for supporting a core in said receptacle in contact with the liquid therein, and means for discharging liquid from said receptacle at a pre-determined rate to bring the level thereof below said core.

2. Apparatus for chilling cores comprising a receptacle adapted to contain a cooling liquid, means for introducing liquid into said receptacle, means for discharging liquid from said receptacle and for determining the level thereof, said last named means being operable by the insertion of a core into said receptacle to vary the liquid level.

3. A chilling apparatus comprising a receptacle adapted to contain a cooling liquid, means for continuously introducing liquid into said receptacle, and means for determining the liquid level therein, and a movable support in said receptacle operatively associated with the liquid level determining means.

- ciated with said last named means to vary the liquid level in said receptacle upon movement of said support.
4. A chilling apparatus comprising a receptacle adapted to contain a cooling liquid, a movable support in said receptacle, means for normally urging said support towards one extreme of its movement, a liquid outlet in said receptacle movable to determine the liquid level therein, said outlet being associated with said support to vary the liquid level upon movement of said support.
5. A chilling apparatus comprising a receptacle adapted to contain a cooling liquid, means for introducing liquid into said receptacle, a movable support in said receptacle adapted to receive an article to be chilled, and a liquid outlet carried by said support and arranged to determine a liquid level normally below an article positioned on said support.
6. A chilling apparatus comprising a receptacle adapted to contain a cooling liquid, means for introducing liquid into said receptacle, a vertically movable support in said receptacle adapted to receive an article to be chilled and to be moved downwardly by the weight thereof, a liquid outlet carried by said support and arranged to determine the level of liquid in said receptacle, said outlet being constructed to lower the liquid level at a pre-determined rate upon downward movement of said support.
7. A chilling apparatus comprising a receptacle adapted to contain a cooling liquid, means for continuously introducing liquid into said receptacle, a vertically movable support in said receptacle having a supporting surface arranged to receive an article to be chilled and to be moved downwardly by the weight thereof, a liquid outlet conduit connected to said support, said conduit having an opening positioned below said supporting surface serving normally as an overflow for the liquid.
8. A chilling apparatus comprising a receptacle, a discharge pipe arranged substantially vertically in said receptacle, a sleeve mounted for limited sliding movement on said pipe, and a support carried by said sleeve, said sleeve having an opening below said support.
9. A chilling apparatus comprising a receptacle, a vertically adjustable guide member carried by said receptacle, a movable support in said receptacle below said guide member, and a discharge conduit carried by said support.
10. A chilling apparatus including a receptacle adapted to contain a chilling liquid, a guide member arranged to guide and support an article to be chilled, and a movable support in said receptacle arranged to be moved downwardly under the weight of an article to be chilled to immerse such article in the

aforesaid liquid, and means for limiting the period of time during which the article remains immersed in the liquid.

11. A chilling apparatus comprising a receptacle adapted to contain a chilling liquid, movable means for receiving an article and moving under the weight thereof to immerse the same in the liquid, and means for limiting the period of time during which the article remains immersed in the liquid.

12. The process of chilling a core comprising dipping the core into a body of cooling liquid, supporting the core in fixed position, and drawing away the liquid at a pre-determined rate to leave the core supported out of contact with the liquid and reduce the temperature of the core a desired amount.

13. The process of chilling articles through a desired temperature range comprising supporting an article in a body of fluid of a pre-determined temperature, and draining away the fluid at a pre-determined rate to leave the article out of contact with the fluid.

In testimony whereof I hereunto affix my signature this 16 day of Oct., 1930.

MARIUS GUYOT.
